INHIBITING TASTE AND ODOR IN
GLYCOLIC ACID

Harry C. Hetherington, Charleston, W. Va., assignor to E. I. du Pont de Nemours & Company, Wilmington, Del., a corporation of Delaware

No Drawing. Original application March 28, 1942, Serial No. 436,712. Divided and this application January 25, 1945, Serial No. 574,634

2 Claims. (Cl. 260—535)

1

This invention relates to the processing of organic compounds and more particularly processing of such compounds to render them free from foreign tastes and odors. This application is a division of S. N. 436,712, H. C. Hetherington, filed March 28, 1942.

Within the past decade so-called stainless steels, generally alloy steels of high chromium content, have been extensively used in the processing of corrosive chemicals and especially in processing chemicals to be used for comestible purposes and for use in potable liquids. The use of these steels has also considerably facilitated the preparation of C. P. products and in many instances it is found possible to prepare the products without the necessity of further purification which ordinarily is required when processing is carried out in vessels constructed of other metals. Certain processes, however, although they are conducted in the presence of only mildly acidic reactants could not be carried out in the alloy steel vessels without imparting odor or taste to the product and in some instances much time consuming and costly clean-up processes were necessary to give acceptable finished products.

An object of the present invention is to provide a process for the treatment of organic compounds in alloy steel to give stable products free from contaminating taste and odor. Another object is to provide a process for the treatment of mildly corrosive organic compounds, or solutions of such nature, in high chromium-alloy steel vessels whereby the products are obtained free from foreign taste and odor. Yet another object is to provide a process for the preparation of organic compounds free from foreign odor or taste which compounds are processed in stainless steel vessels while in the presence of inorganic acids such as sulfuric acid, hydrochloric acid, and the like by effecting the process in the presence of polyvalent metals. Other objects and advantages of the invention will hereinafter appear.

It has been found that liquids can be processed and/or stored in alloy steel vessels and foreign taste and odor avoided even though the products or the reactants from which they are formed are corrosive provided the processing and/or storage in said vessels is conducted in the presence of polyvalent metals such, for example, as manganese, bismuth, cobalt, iron, or especially copper.

The advantageous result is particularly marked for reactions in which organic or inorganic acids are present, such as sulfuric, hydrochloric, oxalic, benzoic, acetic, propionic, tartaric, hydroxyacetic

2

acids, etc., as reactants or catalysts or are present during the recovery of the product from the reaction mixture containing such acids. In the preparation of (methoxymethoxy) ethanol from methylal and ethylene glycol, sulfuric acid is used as the catalyst. (Methoxymethoxy) ethanol is recovered directly by distillation from the reaction product and inasmuch as this compound is used where odors would be objectionable, the distillation is conducted in an alloy steel still. If no polyvalent metal is present the product picks up undesirable odors during the distillation while if there is present 0.0002% or more of a polyvalent metal such as those given above or equivalent concentrations of salts thereof, such as sulfate, acid sulfate, phosphate, chloride, acetate, hydroxyacetate, or the like, the (methoxymethoxy) ethanol is recovered substantially free from foreign odors.

20 Foreign odor and taste can be avoided in organic liquids generally by this method, and it is intended that the term liquids include compounds which may be solids under normal conditions of temperature and pressure but which are processed under liquid phase conditions. For example, in this category are included hydroxyacetic acid and its esters, glycolides, tartaric acid and its esters, citric acid and the like.

The alloy steels referred to in this specification include particularly those which contain a high percentage of chromium, i. e. up to in the order of 30% chromium. For example, the well-known alloy steel containing 18% chromium, 8% nickel, and the remainder mostly iron with traces of carbon, manganese, sulfur, etc., is extensively used as a material for the construction of reactant vessels; as well as steels containing as their major constituent, other than iron, from 12 to 14% chromium. Said alloy steels are especially adapted for use in accord with the invention.

The wide applicability of this method will be appreciated from the following processes in which it has been found to be very effective.

45 *Example 1.*—In the preparation of dimethoxyethyl adipate, a mixture containing adipic acid, ethylene glycol monomethyl ether, and sulfuric acid was processed in an alloy steel reaction still kettle having a composition of approximately chromium 18%, molybdenum 2%, nickel 8%. There was recovered from the reaction mixture a wholly unacceptable product with a sulfurous acid odor. This odor was completely eliminated by introducing 0.0075% of copper as $CuSO_4 \cdot 5H_2O$ 55 into the reaction mixture prior to the reaction.

Similarly the sulfurous odor contaminating diisobutyl adipate, dicyclohexyl adipate, and dimethoxyethyl sebacate, prepared by esterification in alloy steel vessels, was eliminated in the same manner.

Example 2.—A stainless steel storage tank having an approximate composition of chromium 18%, molybdenum 2%, nickel 8%, was used for storing a 90% formic acid solution at normal temperature, the product after a short storage period was highly contaminated. It was found that the contamination could be completely avoided by adding 0.02% of copper as copper formate to the 90% formic acid solution prior to storage.

Example 3.—In the preparation of isobutyl carbamate 0.003% of copper as basic copper carbonate was added to a mixture consisting of 1047 parts of isobutanol and 156 parts of urea. The mixture was heated for several hours at a temperature above 150° C. in a stainless steel apparatus of which some of the internal surfaces were of the approximate composition given in previous examples and others of similar chromium and nickel composition but containing no molybdenum. The product, following removal of unreacted isobutanol and urea, was entirely free of the objectionable foreign odor which it acquires during its preparation in the absence of copper.

Example 4.—A mixture containing 354.6 parts of ethylene glycol, 311.6 parts of a methylal-methanol azeotrope (containing 92% methylal), two parts sulfuric acid, and 0.0075% copper which was added as copper sulfate, was refluxed for six hours in a stainless steel still, the kettle of which was of 18Cr—8Ni—2Mo composition and the heating coils, column and other parts of unmodified 18—8 composition. The reaction product was then distilled, yielding a (methoxymethoxy) ethanol ($\text{CH}_3\text{OCH}_2\text{OCH}_2\text{CH}_2\text{OH}$) fraction which was not only free from foreign taste and odor but which in addition was thermally stable. In the

absence of the copper the product was thermally unstable and possessed a highly objectionable odor.

Example 5.—In the preparation of hydroxyacetic acid 780 parts of methyl hydroxyacetate was hydrolyzed with 820 parts of water in the presence of 0.0016 part of copper. This hydrolysis, the removal of methanol by distillation, the subsequent concentrating of the aqueous solution and the final flash evaporation or remaining free water were all effected in stainless steel equipment of the approximate 18 chrome 8 nickel type. The crystalline hydroxyacetic acid obtained was entirely free of the objectionable odor which had characterized this product when made under similar conditions but in the absence of copper.

I claim:

1. A method of inhibiting the development of foreign taste and odor in hydroxyacetic acid when in contact with chrome-alloy steels, which comprises incorporating in hydroxyacetic acid at least 0.0002% of copper ions based on the weight of the hydroxyacetic acid.

2. A method of inhibiting the development of foreign taste and odor in hydroxyacetic acid during its formation from an ester of the acid which comprises hydrolyzing an ester of hydroxyacetic acid to hydroxyacetic acid in an 18% chromium-8% nickel alloy steel vessel, there being present in solution at least 0.0002% copper.

HARRY C. HETHERINGTON.
